HORST RASSOW, OF BERLIN, GERMANY, ASSIGNOR TO SIEMENS & HALSKE AKTIEN-GESELLSCHAFT, WERNERWERK, OF SIEMENSSTADT, NEAR BERLIN, GERMANY

DOUBLE CONTACT RELAY

Application filed May 27, 1927, Serial No. 194,828, and in Germany September 15, 1926.

This invention relates in general to polarized relays but more in particular to double contact polarized relays, and the object is to make such relays more sensitive and efficient in operation.

Double contact relays are known which have had the fixed contacts located either on both sides of a point of rotation or both of them have been located on one side of the 10 rotatably mounted armature. In every case at least one of the two fixed contacts required spring supports in order that both contact pieces of the armature should make equally good contact. In that case it is impossible for both the fixed contacts to close 15 their circuits quite simultaneously. Furthermore bouncing often occurs owing to the contact pressure not being quite uniform.

The present invention avoids these disadvantages, and at the same time has the advantage that the movable parts have little weight and that all friction at the bearings is done away with, this being achieved by so mounting the armature and so associating 20 the pole shoes with it, that the armature moves parallel to itself and therefore at right angles to its longitudinal axis.

Arrangements of this kind have been known for operating loud speaking telephones, which have the armature rigidly coupled to the telephone diaphragm and mounted on an elastic metal strip located in its longitudinal axis. In that arrangement the armature is surrounded by the telephone coil and 30 its ends lie between the poles of two permanent magnets placed in dissimilar directions. This arrangement could not directly serve as a model, because the two classes of apparatus have different requirements and the 35 very minute moving force of the armature in the known device would be quite insufficient to operate the contacts.

The Figures 1 to 3 inclusive, show by way of example, one method of constructing the 40 novel double contact relay, while Fig. 4 shows an application of the relay as a rectifier. Figure 1 is a section on the line II-II in Figure 2; Figure 2 is a section on I-I in Figure 1; and Figure 3 is a side elevation.

Two permanent magnets 1 and 2 have their

similar poles placed opposite one another and connected by means of soft iron pole shoes 3, 4. In place of the two permanent magnets, a single one could be used. To each of the pole shoes 3 and 4 are screwed two extension 55 pieces 3', 3'', and 4', 4'' arranged in such a manner that one extension piece of each pole shown lies on the front side of the coil 6 opposite the bar shaped armature 5, and the other extension lies on the rear side of 60 the coil but on the opposite side of the armature 5 from the first extension. The armature 5, it will be noted, is surrounded by the coil 6.

According to the polarity momentarily impressed on the armature 5 by the alternating current coil 6, the armature 5 is drawn parallel to itself towards the one or other pair of pole extension pieces 3'', 4' or 3', 4''. In known manner the pole shoe extension pieces 70 can have their position adjustable with respect to one another.

The cylindrical space 7 in the middle of the coil 6 is so large that the armature 5 is quite free to move therein. Slots in the ends of the armature contain insulating plates 8 and 9, which have armature contacts 10 on both sides and are suspended from metal bands 11, 12. The upper ends of the metal bands are fixed 80 into metal blocks 13, to which the wires for conveying current to the contacts are connected. The blocks 13 are mounted on a bridge 14, made of insulating material. The armature contact pieces 10 are connected to the bands 11 and 12 by means of the insulating plates 8 and 9 which act as special strengthening pieces in such a manner as to prevent the armature tipping between the fixed contacts 15 and 16. For this purpose the upper end of the insulating piece 9 is widened. In addition on the other side a special strengthening piece 17 is fastened to the lower part of the band 11. On the other side the band 11 is mounted on the insulating plate 8 so as to be rotatable about the axis formed by the contact 10. The object of this is to enable the supporting band 11 to be turned over in the direction of the axis of the armature after the upper fastening 13 of the band has been loosened, thereby rendering it 100

possible for the armature to be drawn out of the coil 6 at the other side.

Figure 4 shows a circuit arrangement, which permits the novel double contact relay to be used as a rectifier. An alternating current source 18 is connected to a transformer 19, the secondary coil of which is connected to the fixed contacts 15, 16' and 15', 16 of the armature 5. The apparatus consuming direct current, which in the example is shown to be a battery 21 that is to be charged, is connected over a regulating resistance 20 and over the supporting bands 11, 12 of the armature to the latter. The energizing coil 6 surrounding the armature is connected to the alternating current source 18 either in front of the transformer 19 or over the transformer 19, a condenser 22 being preferably inserted in the circuit for the purpose of adjusting the phase.

What is claimed is:

1. In a polarized relay, a pair of permanent horse shoe magnets, a coil mounted between said magnets, an armature extending through the center of said coil and controlled thereby, a pair of pole shoes attached to said magnets and disposed on each side of said coil, each end of said armature disposed between said pole shoes, and, a pair of elastic electrical conducting bands, insulated from and supported by said pole shoes, and attached to each end of said armature for supporting the same.

2. In a polarized relay, a pair of permanent horse shoe magnets, a coil mounted between said magnets, an armature extending through the center of said coil and controlled thereby, a pair of pole shoes attached to said magnets and disposed on each side of said coil, each end of said armature disposed between said pole shoes, and, a pair of elastic electrical conducting bands, insulated from and supported by said pole shoes, and attached to each end of said armature, said elastic conducting bands attached to each end of said armature by means of flat insulating pieces and strengthening pieces on said bands.

3. In a polarized relay, a pair of permanent horse shoe magnets, a coil mounted between said magnets, an armature extending through the center of said coil and controlled thereby, a pair of pole shoes attached to said magnets and disposed on each side of said coil, each end of said armature disposed between said pole shoes, and a pair of elastic electrical conducting bands, insulated from and supported by said pole shoes, and attached to each end of said armature, said elastic conducting bands attached to each end of said armature by means of flat insulating pieces and strengthening pieces on said bands, one of said bands being rotatably attached to said armature to permit withdrawal of the armature from said coil.

4. In a relay, an armature passing through

the center of a coil and having contacts on each end thereof, means for suspending said armature on an axis parallel to itself, and means for moving said armature bodily to alternate positions around said axis so that contacts on the same side and on both ends of the armature are closed at the same time.

In witness whereof, I hereunto subscribe my name this 22nd day of April, A. D. 1927.

HORST RASSOW.
